UNITED STATES PATENT OFFICE.

ROBERT P. SCOTT, OF CADIZ, OHIO.

GREEN-PEA, BEAN, AND COW-PEA HULLER.

1,107,207.

Specification of Letters Patent. Patented Aug. 11, 1914.

Application filed September 30, 1913. Serial No. 792,578.

To all whom it may concern:

Be it known that I, ROBERT P. SCOTT, a citizen of the United States, residing at Cadiz, Harrison county, Ohio, have invented 5 certain new and useful Improvements in Green-Pea, Bean, and Cow-Pea Hullers, of which the following is a specification.

My invention relates to machines for hulling green peas, cow peas, lima and other 10 beans and kindred vegetables, especially but not solely from the vines.

One of the objects of my invention is to improve upon the machine heretofore used in this art and to improve the product obtained therefrom and the capacity of such 15 machines.

More particularly my object is to improve upon the construction of the machine with relation to its simplicity, durability, facility 20 of handling and shipping, taking it apart and setting it up, together with ease of transportation, moving it from place to place, decreasing its weight and the location of the center of gravity so as to make the 25 machine more stable and portable.

Another object is to secure economy of construction and to make the machine more practicable for the various uses for which it is intended.

My invention consists in an improvement 30 in the general arrangement of the driving mechanism and the construction of the separating drum whereby the driving power for the drum is automatically increased upon 35 increase of load or resistance encountered by the drum.

My invention consists further in an automatic feeding device for feeding the material to the machine consisting of a rake 40 and means for operating it.

My invention consists further in providing the pea hulling machine with a straw carrier formed of a cylindrical outer screen and a worm within the screen for delivering 45 the material from the machine.

The various improvements herein pointed out are the result of actual use and necessity as developed by the operation of the machines in practice.

With the above and other objects in view, 50 my invention consists more particularly in the parts, improvements and combinations set forth in the claims.

Heretofore machines for hulling green 55 peas have been mostly driven by gear wheels

meshing into a cog wheel on the outer drum, the said gear wheels being driven by a pinion upon the countershaft. The countershaft is driven by the main driving shaft which carries the inner drum. In my former machines a single shaft was driven from the engine which shaft in turn connected with a counter shaft running over the top of the machine, the counter shaft driving the outer drum by means of sprocket wheels 60 upon a shaft and a chain circling the outer drum, and the sprocket wheels. In accordance with my present invention, the outer drum is driven by means of travelers which carry the drum, and drive it through frictional contact, whereas in prior machines the travelers were mere idlers and were turned by the drum. I have also done away with the counter shaft over the top of the machine, thus saving head room. The travelers 65 carry sprockets and are rotated positively by a sprocket chain driven from the central shaft and suitable means are provided for turning the outer drum when the resistance to rotation increases by reason of 70 heavy work.

Turning now to the drawings: Figure 1 is an end elevation of my new huller, showing the feed hole and the driving chains. Fig. 2 is a side elevation and section of the 75 feed and discharge end of the machine showing the feeding device and the straw carrier. Fig. 3 is a cross section of both inner and outer drum, the travelers and the end rings of the outer drum. Fig. 4 is a detailed 80 view in section of an elevating rib and of the channel iron and ring in which it is anchored. Fig. 5 is a plan view of a screening 85 net for the outer cylinder.

The end frame 1 (Fig. 1) supports the 90 driving mechanism. The main driving shaft 2 carries a sprocket 3 engaging chain 4, the latter driving sprocket wheel 5 removably mounted on the end of shaft 6, sprocket wheel 7 removably mounted on 100 the end of shaft 8, and sprocket wheel 9 removably mounted on the end of shaft 10. The slack of the chain occurs between the sprocket wheels 3 and 9. All three shafts are positively driven by the same chain. 105 By using a fourth sprocket above the beater shaft and by having a single open chain engage all four sprockets, the drum and the beater shaft are driven in the same direction. The center of gravity of the driving 110

system is kept low and beneath the top of the machine.

A drum 11 is secured to shaft 2 and beaters 12 extend radially from this drum and are bolted to it at 13. The beaters are made in two parts and bolted together at 14. Means are provided for driving the apron from the sprocket chain drive. Mounted on shaft 6 is a small sprocket 15 engaging sprocket 10 wheel 16 on shaft 17 by means of chain 18. Apron roller 19 is securely fastened to shaft 17, thus operating the roller upon which the cleaning and separating apron 20 is carried. By this means the speed of the apron 15 may be readily varied by simply changing the small sprocket 15. It will be observed that a change of speed of the driven parts may be readily effected since one change of the central sprocket 3 will simultaneously 20 vary the speed of all the driven parts. The sprocket 15 controls the feed of the apron and any change in the size of the sprockets 3, 9 and 5 will alter the speed of the outer drum. Since these sprockets are on exposed 25 ends of the several shafts, it will be seen that all adjustments and changes are easily made.

Heretofore efforts to turn the outer drum by frictional action have been unsuccessful. 30 In accordance with my present invention, however, I provide a third traveler 21 located at the top and between the other two travelers 22 and 23 as shown in Figs. 2 and 3. All the travelers bear upon the drum. 35 The outer or separating drum 24 carries lifting ribs 25. Suitable means are provided so as to automatically increase the pressure of the travelers upon the drum when the load of the machine increases or when it 40 becomes overloaded, or if the drum tends to stick for any reason. To accomplish this result the third traveler 21 is mounted upon the same shaft 8 which carries the sprocket 7. These parts have a vertical motion, being 45 mounted in an arm 26 which is free to swing about its pivot 27. It will thus be seen that any pull on the chain 4 acts to pull down on the sprocket 7, thus increasing the pressure of all of the travelers upon the end 50 rings of the outer drum.

In order to sustain the increased pressure which is brought upon the outer drum, when the sprocket 7 and corresponding traveler is pulled down upon it, I make the end circles or rings 28 of iron and of a cross section to withstand the pressure. As shown in 55 Figs. 1, 2, 3 and 4, these rings are made of channel iron. By reason of this special cross section the iron rings are also well 60 adapted for and form a strong anchor for the elevating ribs. The channels are tapered on their insides and the ends of the elevating ribs 25 (see Figs. 2 and 4) are fitted into the channels, a bolt 26 helping to 65 firmly unite the parts. By this means no

displacement of the elevating rib can occur to which my old device was liable when I depended merely upon a bolt for bolting the rib to the drum.

In accordance with my invention means 70 are provided for feeding the material to the drum and a straw carrier for discharging the material from the drum. The feeding mechanism includes a chute 27 Fig. 2 which directs the vines into the feed hole 75 28. This chute may be slanted more or less in order to assist the forward movement of the vines. A rake 29 with teeth 30 is driven by a crank 31 from the sprocket shaft 10 through intermediate connections consisting 80 of jointed levers 32 and 33. The teeth of the rake ride over the vines as the rake is withdrawn and push them forward into the feed hole when it is advanced. The teeth 34 at the bottom of the feed chute prevent 85 the material from returning with the rake when the latter is withdrawn.

My straw carrier 35 Fig. 2 is constructed in the form of an Archimedean screw and consists of a cylindrical wire screen 36 with 90 a screw 37 upon the inside thereof. It is driven through a universal joint 38, connected to the end of the revolving shaft 10. Suitable gearing 39 and 40 drive the screen. The gear 39 is mounted upon the shaft 95 carrying one member of the universal joint. The material when discharged from the perforated screen end of the drum drops into the chute 41 and is delivered to the screw 37. The screw and screen elevate and discharge the straw and any peas that may remain are sifted out by the screen, collected and saved. The separating drum is of polygonal cross-section and carries at its discharge end a sifting screen 42 made of wires. 100

In accordance with my invention I provide a special screening surface for the body of the separating drum 24. This consists of a pliable netting of fibrous strands such as the cord netting, shown in Fig. 5. I may 110 make use of an ordinary seine or fish net, but in order to make use of a heavier thread I prefer to make a net by using large sized cord crossed at suitable intervals to form the correct size of opening and staple the 115 cords together instead of knotting them. Knots take up a great deal of space with small threads. A very useful feature of the netting is that it may be stretched in one direction which permits it to contract in the 120 other so that any quadrilateral shape can be attained for the mesh. By drawing the net into a lozenge or diamond shape, the apertures for the discharge of the hulled product can be restricted in size in one direction and since products like green peas are substantially round, the meshes may be made just large enough for the peas to pass through 125 and no more.

As shown in Fig. 5, the screen surface 130

may be made in panels, in each of which the netting is mounted or stretched upon a suitable frame 24^a having pins or the like 24^b, the said frame and pins constituting means for maintaining the shape of the screen openings and supporting the screen fabric. The shape of the openings may be varied if desired by stretching the net and refastening it by means of the pins. For lima beans an aperture elongated in one direction and contracted in the other is a better shape than a round hole, since the lima bean itself is elongated. Another advantage of the netting is that if the aperture is slightly smaller than the pea berry, the pressure of the vines upon the peas will force them through openings bounded by the pliable cords whereas the containers or pods are held back by the netting. The netting is also much cheaper than perforated rubber and more economical.

Having thus described my invention, its advantages will be apparent. Machines of this character must be hauled from farm to farm in hulling cow peas so that any weight at the top is objectionable, making the machine top heavy. The heavy countershaft and sprocket wheels of considerable weight over the top of the machine as used in my prior devices, are done away with. The present machine concentrates the weight lower down so that the center of gravity of the machine as a whole is near the ground and hence the machine is much safer, both when being transported and when in use.

Having thus described my invention, its operation will be readily understood. Changes may be made in carrying out the leading features of the invention without departing from the principle. Thus instead of sprocket chains equivalent means may be used.

What I claim and desire to secure by Letters Patent is:

45 1. In a machine for hulling peas, beans and the like by impact, the combination of an outer separating drum provided internally with lifters, an inner concentric shaft carrying a sprocket, said shaft being provided with an inner drum carrying beaters separated by longitudinal clearances from the lifters, friction travelers frictionally engaging and carrying the outer drum, sprockets secured to said travelers for driving them, a fourth sprocket above said inner shaft, a single driving chain running over the inner shaft sprocket, under said traveler sprockets, and over the fourth sprocket, thus causing the two concentric mechanisms 50 to revolve in the same direction.

60 2. In a machine for hulling peas and the like, the combination of an outer separating drum, travelers engaging said drum, a chain engaging and driving said travelers, and means for automatically increasing the

pressure of one of said travelers upon the drum when the drum encounters additional resistance.

3. In a machine for hulling peas and the like, a separating drum adapted to receive the vines, means for supporting and driving said drum and a single driving chain conveying power to said means and automatically increasing the pressure between said means and said drum when the drum encounters additional resistance.

4. In a machine for hulling peas and the like, an outer separating drum, channel irons forming the ends of said drum and elevating ribs anchored in said channel irons.

5. In a machine for hulling peas and the like, an outer drum, rings consisting of channel shaped iron forming the ends of said drum, a pair of travelers engaging each of said rings, a third traveler for each ring engaging the same at a point between the other two and means whereby said third traveler automatically adjusts itself to the change in the load upon one or both of the end rings of the drum.

6. In a machine for hulling green peas and the like, the combination of a separating drum, two end rings formed of channel iron forming the ends of the drum, three travelers engaging each end ring, sprockets secured to said travelers and a single chain engaging and driving said sprockets.

7. In a machine for hulling green peas and the like, the combination of an outer separating drum, a plurality of travelers engaging and driving said drum, sprockets secured to said travelers, a central driving shaft carrying beaters and having a sprocket, a single sprocket chain engaging all of said sprockets and passing over the shaft sprocket and beneath the traveler sprockets whereby the separating drum and beater shaft are rotated in the same direction at different speeds, a cleaning apron, and a sprocket chain operating to drive said apron from one of the traveler shafts.

8. In a machine for hulling green peas and the like, the combination of a rotary separating drum, driving means including a driving chain for driving said drum, a feeding device for feeding the material to said drum, a straw carrier for discharging the material from the exit end of the drum, end rings forming the ends of said drum and an oscillating traveler for automatically increasing the pressure upon the drum.

9. In a machine for hulling green peas and the like, the combination of a separating drum, an inner beater carrying drum and a cover or screening surface for the separator consisting of a net of soft fibrous pliable strands, said strands inclosing openings the walls of which are adapted to be variable in shape, and means for maintain-

ing the shape and supporting the screening surface.

10. In a machine for hulling green peas and the like, the combination of a separating drum, an inner beater carrying drum, and a cover or screening surface separating drum consisting of a woven net of cord the openings of which are adapted to be variable in shape, and means for maintaining 10 the shape and supporting the screening surface.

11. In a machine for hulling green peas and the like, the combination of a drum for elevating the peas, said drum being provided with a sifting screen made of soft, 15

pliable material provided with openings the walls of which are adapted to be variable in shape, and means for maintaining the shape and supporting the screen, a beater carrying drum, a chain driving both drums, 20 a feeding device for feeding the material to the drums, a straw carrier, and a cleaning apron beneath said screening drum.

In testimony whereof, I have signed my name to this specification, in the presence 25 of two subscribing witnesses.

ROBT. P. SCOTT.
